DESIGN FOR A FOUNTAIN PEN CLIP OR SIMILAR ARTICLE

Milford Guy Sypher, Belleville, N. J., assignor to
The Chilton Pen Company, Inc., Long Island
City, N. Y., a corporation of New York

Application April 13, 1935, Serial No. 56,357

Term of patent 14 years

To all whom it may concern:

Be it known that I, Milford Guy Sypher, a citizen of the United States, residing in Belleville, county of Essex, State of New Jersey, have invented a new, original, and ornamental Design for a Fountain Pen Clip or Similar Article, of which the following is a specification, reference being had to the accompanying drawing, forming a part thereof.

The figure is a perspective view of a clip, illustrating my new design.

I claim:

The ornamental design for a fountain pen clip or similar article, substantially as shown.

In witness whereof, I have hereunto affixed my hand and seal, this 11th day of April, 1935.

MILFORD GUY SYPHER.
